US00D961590S

(12) **United States Design Patent** (10) Patent No.: **US D961,590 S**
(45) Date of Patent: **** Aug. 23, 2022**

(54) **MONITOR FOR COMPUTER**

(71) Applicant: **LG ELECTRONICS INC.**, Seoul (KR)

(72) Inventors: **Seongyeong Park**, Seoul (KR); **Daihyung Ryu**, Seoul (KR); **Hyeongyeol Kim**, Seoul (KR)

(73) Assignee: **LG ELECTRONICS INC.**, Seoul (KR)

(**) Term: **15 Years**

(21) Appl. No.: **29/735,878**

(22) Filed: **May 26, 2020**

(30) **Foreign Application Priority Data**

Dec. 6, 2019 (KR) 30-2019-0059054

(57) **CLAIM**

The ornamental design for a monitor for computer, as shown and described.

DESCRIPTION

FIG. 1 is a front, right side, perspective view of a monitor for computer showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines indicate unclaimed portions of the article that form no part of the claimed design.

1 Claim, 8 Drawing Sheets
